AUTOMOBILE FLOOR MAT

James H. Barnes, Wadsworth, Ohio

Application November 8, 1955, Serial No. 38,786

Term of patent 14 years

(Cl. D9—6)

Fig. 1 is a top plan of an automobile floor mat embodying my new design; and

Figs. 2, 3 and 4 are enlarged vertical sections on lines 2—2, 3—3 and 4—4, respectively, of Fig. 1.

I claim:

The ornamental design for an automobile floor mat, as shown.
